[57] CLAIM

The ornamental design for a crib hammock, as shown and described.

DESCRIPTION

FIG. 1 is a top plan view of a crib hammock showing
my design;

FIG. 2 is a bottom plan view;

FIG. 3 is a side view;

FIG. 4 is an end view; and

FIG. 5 is a top perspective view of the crib hammock

The crib fragmentarily depicted in dotted outline in
FIG. 5 is for illustrative purposes only.
